UNITED STATES PATENT OFFICE.

HERBERT R. BRUNNER, OF NEW YORK, N. Y., ASSIGNEE, BY MESNE ASSIGNMENTS, TO
VAN KANNEL REVOLVING DOOR COMPANY, OF NEW YORK, N. Y., A CORPORATION
OF NEW JERSEY.

AIR-PREHEATING DEVICE FOR STOVES AND FURNACES.

Application filed December 31, 1918. Serial No. 269,034.

To all whom it may concern:

Be it known that I, HERBERT R. BRUNNER, a citizen of the United States, residing at New York, in the county of New York and 5 State of New York, have invented certain new and useful Improvements in Air-Preheating Devices for Stoves and Furnaces, of which the following is a specification.

This invention relates to improvements in 10 air preheating devices for aiding combustion in furnaces and more particularly to such a device adapted for attachment to the furnace door, and to extend into the combustion chamber.

15 The primary object of the invention is to deliver to the combustion zone, or the combustion chamber of a furnace, the proper amount of adequately preheated air, for all draft conditions, that is to say, without excessive air flow under high draft and with 20 adequate air flow under minimum draft, and to provide means for adequately preheating said air.

I am aware that many devices of this 25 character have been devised in which the air is baffled in its passage through the preheater, but these have apparently merely taken into consideration, the idea of retarding the flow of the air so as to give it time 30 to become heated by contact with the very considerable amount of metallic heating surface formed by baffles variously shaped and variously arranged within the device. The element of time during which the air in passing 35 through the preheater, is exposed to the heating surface of the preheater, does not seem to have been taken into serious account, the result being that such devices amounted to nothing more than open passages leading 40 from the outside to the inside of the furnace, virtually without control, and with no perceptible rise in temperature.

My experiments have demonstrated that 45 the success of a device of this character depends upon the necessary control of the air through the preheater under varying draft conditions, and upon the volume, as this must be substantial and upon supplying an adequate amount of heat to the air in passing 50 through the device, to bring it to the proper temperature to be delivered into the furnace and that the control referred to as a practical proposition must be an automatic control, that is to say, a control that is in-

herent in the device itself, so that it acts automatically to deliver a substantial and proper quantity of adequately preheated air. 55

In the construction about to be described, I am enabled to employ channels of large cross sectional area, and consequently large 60 capacity, which, while having in common the feeding function of the air, are so proportioned and arranged with relation to each other, as to cause the device to functionate differently in some particulars, in different 65 parts of the device. To accomplish this, I provide one or more large channels, which are, in effect, storage or reservoir preheating chambers or channels (and these will be referred to hereinafter as channels) in 70 which the air is more nearly at a state of rest than the air in the other or feeding channels, which are in communication with the storage or reservoir, thus providing sets of 75 channels having different characteristics, which channels may be termed "primary and secondary heating channels," the secondary channels being the control element of the device. Between the various channels, both large and relatively small, I arrange for 80 ninety and one hundred and eighty degree reversals of the air, by the provision of the transfer passages situated at the ends of the channels, wherethrough the air is transferred from one channel to the other, which 85 is the control feature of the device.

By the reversals referred to retardation of air is introduced in my invention, and by the use of relatively large storage reservoirs or channels, exposed to the heat in the furnace, the relatively slow moving mass of air is thoroughly and uniformly preheated and by the employment, in connection with these relatively large channels, of a series or plurality of comparatively attenuated 90 channels or channels of smaller cross sectional area, which are in communication with the reservoir channels, and with each other, through transfer openings arranged at the alternate ends of the channels, by 95 which the direction of flow of the air is sharply reversed, and thereby retarded, an automatic control is accomplished and the device rendered capable of delivering only the required and desired quantity of adequately preheated air under minimum draft, which amount will be increased under 100 increase in draft, but will be held to the 105

maximum requirements under maximum drafts. By the use of primary and secondary heating channels, the former being that or those I have referred to as storage or reservoir channels, with the sharp reversals between them, I am free to use relatively large channels for primary heating, which are large enough relative to the secondary channels, to supply the required air flow, with low velocity. The condition of air flow in the large channel or channels being more nearly at a state of rest, the requisite condition for facilitating the heating of said air is greatly improved, as the slow moving mass of air will take up heat more readily from the highly heated surfaces of the device than if it were carried forward at high speed, the comparative slowness of movement, giving the air an opportunity of intermingling and circulating in contact with the heated walls of the chambers or channels. It is necessary, in order to get good results, that all of the molecules of the air be brought successively into contact with the heated surface, for the reason that air is not a good conductor of heat if at all, and the molecules of the air must be heated by convection, hence the large channels or chambers, in which the air is maintained comparatively at a state of rest. Not only does the provision of large preheating or reservoir channels serve their purpose as storage chambers, but they present a large area of heating surface and consequently have the capacity for more highly heating the air brought in contact with the surfaces.

In the drawings illustrating the invention—

Figure 1 is a side elevation of a portion 40 of a furnace of ordinary construction, with the part adjacent the fire door broken away to show the preheater attached to the furnace door.

Figure 2 is a vertical sectional view of 45 the preheater taken about on line 2—2 of Figure 4.

Figure 3 is a horizontal sectional view taken on line 3—3 of Figure 2.

Figure 4 is a vertical longitudinal section 50 of the heater, taken about on line 4—4 of Figure 2, looking toward the front or intake side of the casing, and

Figure 5 is an enlarged perspective view, 55 partly broken away, designed to show the entire internal construction of the device.

It will be understood at the outset that the preheater is made of metal in different sizes, and adapted for attachment to the fire door of any well-known type or style of furnace, or it may, in some instances, be cast as a part of the fire door, as the exigencies of the case may require. It is adapted to occupy a space above the grate and extends, when the door is closed, a considerable distance into the combustion cham-

ber of the furnace, in position to deliver the adequately preheated air into the products of combustion from the fire bed.

Referring to the drawings, A designates a furnace of any approved construction, B the fire door, C the fire door damper, D the grate, and E the ash pit door.

The numeral 1 designates the preheater which is a metallic casing generally rectangular in shape, and of oblong contour, and is formed with a top plate 2, bottom plate 3, end plates 4 and 5, front plate 6, and rear plate 7, the plate 7 inclining inwardly as indicated at 8, and joining the bottom plate 3, so that the casing presents to the fire in the combustion chamber of the furnace, a beveled surface which deflects to some extent, the heat and prevents the burning or fusing of the metal from intense heats. The plates referred to are cast integral and at the bottom and top of the casing I provide ears 9 provided with apertures 10, for the passage of bolts 11, by which the preheater is attached to the furnace door B, the form illustrated being one adapted for attachment to the door, rather than to form an integral part of the door casting.

As before suggested, the terms "channels" and "chambers" may be used interchangeably, because while the vertical and horizontal partitions form, with the walls of the casing, channels, they also form chambers, and particularly is this true of the bottom channel 12, which is storage or reservoir chamber or channel, which is, relative to the other channels, of large cross sectional area and consequently of relatively large capacity. This channel has direct communication with the outside air, through the usual opening in the furnace door, through inlet opening 13 in the inset portion 14 of the front plate 6 of the casing, which inset portion extends, as illustrated best in Figure 4, for substantially the entire length of the preheater, thus forming, when the device is against the flat surface of the furnace door, a horizontal chamber for the lateral circulation of the air across the entire face of the preheater, in order that it reach the opening 13 from points encompassing the entire area of the damper arrangements of the furnace door.

The lower chamber 12, sometimes called a storage chamber, is formed by horizontal partitions 15, vertical wall 6, rear wall 8, bottom 3, and portions of end walls 4 and 5. Vertical chamber 17 is formed by a part of horizontal partition 18, vertical wall 16, part of end wall 5, and parts of vertical partition 20 and front wall 6. The partition 15 is provided with a transfer opening 15', through which communication is established between the outside atmosphere and the reservoir or storage channel 12. Intermediate of the partitions 15 and 18 is a horizon-

tal partition 19, which extends for about one half of the length of the casing, and is integral with the front wall of the casing and with a vertical partition 20 which extends from the top of the casing to the partition 15, this partition being, like the others, integral with the walls of the casing. By this arrangement of vertical and horizontal partitions in the front part of the casing, 10 control channels 21, 22 and 23 are formed. The channel 21 is in communication with the reservoir or storage channel through transfer passage 24, and the channel 21 is in communication with the channel 22 by large transfer passage 25 and the channel 22 is in communication with the top channel 23 through transfer passage 26, as clearly shown in Figure 4.

The partition 15 as shown in Figure 2 20 extends entirely to the rear plate and with said plate, and a partition 27, forms a distributing channel 28 in communication with a similar channel 29, through transfer passage 30, formed in the partition 27, and the rear of the casing opposite these two last mentioned channels is provided with a series of discharge openings 31, through which the adequately preheated air passes to and mingles with the products of combustion in 30 the combustion chamber of the furnace, after it has been, by the draft conditions of the furnace, drawn from the lower storage or reservoir channel and passed vertically and horizontally through the parts of the 35 casing above the large channel, being meanwhile subjected to sharp reversals and retardation effects, the flow of the air being upon 90° and 180° reversals.

The vertical partition 20 is provided near 40 one end of the casing with a transfer passage 29', through which communication is established between the channel 23 and the channel 29.

In operation, the damper of the fire door 45 is adjusted according to the requirements of the particular furnace, having regard for the capacity of the furnace and the size of the preheating device best adapted for the range requirements of the furnace and 50 air passing through the damper, passes into the chamber formed between the front wall of the casing of the inside of the furnace door, and through the inlet opening 13, downwardly to the reservoir or storage 55 channel 12, and passes with a comparatively slow movement, due to volume of air, for the entire length of the casing, through transfer opening 24, into the channel 21, through transfer passage 25 to the channel 60 22, and through channel 22 to the top channel 23, through transfer opening 26, and entirely across the top of the casing, and into the front channel 29 through transfer opening 29' and is distributed throughout 65 the length of the channel 29 to the opposite

end of the casing, where it passes downwardly to the channel 28 through transfer passage 30, from which channels 29 and 28, the air passes in comparatively small streams, through the discharge openings 31, 70 where it mixes with the products of combustion in the furnace.

Having thus described my invention, what I claim is:

1. An air preheating device for promoting combustion in furnaces and the like, comprising a casing provided at its bottom with a storage channel of comparatively large cross sectional area, and having an air inlet communicating directly with the 75 said channel, a plurality of vertical and horizontal partitions which, together with the walls of the casing, form horizontal channels in communication with each other, and with the storage channel in series, 80 through suitable transfer passages, and suitable discharge openings in the rear of the casing, through which air is discharged into the furnace after having passed back and forth through the various channels. 90

2. An air preheating device for aiding combustion in furnaces and the like, having in the lower portion thereof a reservoir channel of comparatively large cross sectional area and capacity, and having a vertical passage, and an inlet opening above the reservoir channel and communicating therewith through said vertical passage so that air flowing into the preheater will pass first into the reservoir or storage channel, 95 a horizontal partition extending entirely across the casing and forming the top wall of the storage channel, and a vertical partition intersecting the horizontal partition and extending to the top of the casing, there being horizontal partitions intersecting the vertical partition which form, with the walls of the casing, horizontal channels, transfer passages arranged in the partitions, 100 whereby communication in series between the channels is established, and suitable discharge openings in the rear of the casing through which air, after it has passed through the channels is introduced into the combustion chamber of the furnace. 110

3. A preheating device for aiding combustion in furnaces and the like, comprising a casing having therein a horizontal partition extending entirely across the casing, thus, with the walls of the casing, forming 115 a storage chamber, an air inlet in the front of the casing having direct communication with the storage chamber, a vertical partition intersecting the horizontal partition and extending to the top plate of the casing and for the full length of the casing, a horizontal partition intersecting the rear of the casing and the vertical partition, thus 120 dividing the back part of the casing into two horizontal channels, horizontal parti- 125

tions intersecting the vertical partition and the front wall of the casing, thus, with the walls of the casing, forming a second set of channels at the front of the casing, there being transfer openings in the last mentioned horizontal partitions arranged at alternate ends of the casing, whereby communication is established between the reservoir chamber and the front set of channels, and a transfer passage in the vertical partition, whereby communication is established between the upper front channel and the

upper rear channel, and a transfer passage in the rear horizontal partition, whereby communication is established between the two rear channels, and suitable discharge openings in the rear wall of the casing through which air is discharged from the rear channels. 15
